UNITED STATES PATENT OFFICE.

EDWARD IRVING LUDWIG, OF BABYLON, NEW YORK.

LEFT-OVER ICE-BOX FILE.

1,278,695.

Specification of Letters Patent. Patented Sept. 10, 1918.

Application filed April 20, 1917. Serial No. 163,502.

To all whom it may concern:

Be it known that I, EDWARD I. LUDWIG, a citizen of the United States, and a resident of Babylon, in the county of Suffolk and State of New York, have invented a new and Improved Left-Overs Ice-Box File, of which the following is a full, clear, and exact description.

This invention relates to means for storing or filing away in an ice box fresh foods or left-overs, in such a manner as to insure efficient refrigeration with a minimum amount of ice, and at the same time take care of a large amount of food in a comparatively small capacity ice box or refrigerator.

The invention has for its general objects to provide an improved receptacle and arrangement of receptacles whereby foods can be compactly stored in a sanitary and effective manner, the receptacles being so constructed that one can fit in another so that covers are dispensed with, except for the topmost receptacle of a group, and furthermore, the receptacles are so shaped that it is impossible to place piles or groups of receptacles so close together as to interfere with effective circulation of the air.

A more specific object of the invention is the provision of a receptacle having corrugations formed adjacent the top and in one side, so that when this corrugated or scalloped side of the receptacle is in contact with the flat side of another receptacle, ports or passages are formed through which the air can circulate, and the cover for such a receptacle has a scalloped edge so as to close the scallops or corrugations of the receptacle, thereby keeping the contents of the receptacle covered and in a sanitary condition. The receptacles are slightly tapered so that one can fit in another to such a depth as not to close the corrugations, whereby cold air can circulate in the receptacles, and preferably the receptacles are made of enamelware or the like, so that they can be used as cooking utensils to thereby do away with the necessity of transferring the food to other pots or pans. To insure the sanitary conditions the corners and edges are rounded to prevent the accumulation of food and render cleaning easy.

With such objects in view, and others which will appear as the description pro-

ceeds, the invention comprises various novel features of construction and arrangement of parts which will be set forth with particularity in the following description and claims appended hereto.

In the accompanying drawings, which illustrate one embodiment of the invention and wherein similar characters of reference indicate corresponding parts in all the views,

Figure 1 is a front view of a refrigerator with the food containers or receptacles piled therein, few of the containers being partly broken away;

Fig. 2 is a plan view of two containers placed together and the cover of one of the containers partly broken away;

Fig. 3 is a sectional view on the line 3—3, Fig. 2; and

Fig. 4 is a perspective view of one of the containers with the cover raised.

Referring to the drawing, A designates an ordinary refrigerator in the compartments of which are arranged food containers or receptacles B, which may be of different sizes and shapes according to the nature of the food stored. Certain of the containers are of such size as to admit of their being piled one on top of another so that space is economized.

Each container comprises a suitably shaped body 1 made of enamel, metal, earthenware or the like, and the corners and edges inside are preferably rounded. The wall 2 of each receptacle has along its top edge substantially conical flutes, corrugations or scallops 3, which serve to prevent an adjacent receptacle from being placed in too close proximity thereto. These flutes extend about an inch or so from the top edge but they are not closed when one receptacle is placed in another, as shown in Fig. 2. The receptacles are slightly tapered downwardly so that one above fits within one below it without the bottom of the upper receptacle coming into contact with the food. For the receptacles not covered by another one set thereinto, a cover 4 is employed, which cover has a scalloped edge 5, so that the scallops thereof will fit into the corrugations or flutes 3 and effectively close the receptacle. Lugs or equivalent devices 6 on the ends of the cover serve to enable it to be easily removed, or ventilating or finger-holes

7 perform the same function. The cover has beveled edges 8 so as to easily fit on the receptacle by constructing and arranging the receptacles in the manner described and 5 shown, and numerous vertical passages are formed between adjacent receptacles or between certain of the receptacles and the walls of the refrigerator, and by means of these passages the cold air can circulate 10 freely in the refrigerating compartment and also in close contact with each receptacle, so that effective refrigeration of the contents is insured.

Furthermore, the foods will be kept separate and one kind of food will not be affected by foods of another kind.

From the foregoing description taken in connection with the accompanying drawings, the advantages of the construction and 20 method of operation will be readily understood by those skilled in the art to which the invention appertains, and while I have described the principle of operation, together with the device which I now consider to be the best embodiment thereof, I 25 desire to have it understood that the device shown is merely illustrative and that such changes may be made when desired as fall within the scope of the appended claims.

30 Having thus described my invention, I

claim as new and desire to secure by Letters Patent:

1. A left-overs ice box file comprising a plurality of rectangular containers each of the same construction and adapted to fit one within another, whereby any one of the containers may be at the top, each container being open at the top and tapering downwardly, whereby the bottom of an upper container fits into the next one below it, the four walls of each container having their upper edges in a common plane, and one wall being provided with corrugations extending downwardly to a point below the bottom of an interfitting superimposed container, 35 whereby the corrugations form ventilating passages, and a cover adapted to fit any one of the containers and having one edge shaped to conform to the corrugations. 40

2. A receptacle for a left-overs ice box file, comprising a body having imperforate walls and an imperforate bottom, the receptacle being open at the top and tapering downwardly, and the upper edges of the 45 walls being in a common plane and one wall having corrugations extending downwardly from the top edge, and a cover resting on the top edges of the walls and one edge of the 50 cover being shaped to fit in the corrugations. 55

EDWARD IRVING LUDWIG.
